UNITED STATES PATENT OFFICE.

FREDERICK KOSKUL, OF ST. LOUIS, MISSOURI.

VENeer.

SPECIFICATION forming part of Letters Patent No. 289,005, dated November 27, 1882.

Application filed March 20, 1883. (Model.)

To all whom it may concern:

Be it known that I, FREDERICK KOSKUL, a citizen of the United States, residing in the city and county of St. Louis, and State of Missouri, have invented an Improved Veneer, of which the following is a specification.

My improved veneer consists, first, of a sheet or strip of transparent, partially transparent, or opaque varnish or equivalent material, with 10 ornamenting particles of pearl-shell or other fragments, or geometrical pieces of either circular, oblong, square, prismatic, octagon, lozenge, or analogous known forms of any suitable material—such as metal, stone, glass, 15 wood, bone, or a combination of any of the same—embedded into its body, and the varnish or equivalent material, as well as the ornamental fragments or geometrical pieces forming the body proper of the veneer, being applied to and supported by a paper or cloth foundation, which serves to sustain the materials while the veneer is being manufactured, as well as while being applied upon a base or 20 any article, or in any place, this paper or cloth foundation being readily removable, so as to expose to view the varnish or equivalent surface and the embedded ornamentations, or both such ornamentations and portions of the base upon which the veneer is placed; second, 25 of a veneer made of varnish or equivalent material, and with fragmental ornaments—such as pearl-shell or other fragments, or geometrical pieces of either circular, square, oblong, lozenge, prismatic, or other analogous known 30 forms of any suitable material—such as metal, stone, glass, wood, or other known suitable substances, or a combination of any of the same—and with both a paper foundation and a paper or woven cloth backing, whereby the 35 veneer or its equivalent and fragmental ornaments or geometrical pieces, after having been pressed between rollers, are made to form a veneer of uniform thickness and level and smooth.

40 The varnish veneer, or veneer of equivalent material, with its embedded fragmental or geometrical ornaments, is sustained while being manufactured, and also protected and sustained while being applied to any article or in 45 any place, and which veneer can be cemented or glued firmly in position by any suitable

means, and can by removal of its paper foundation have its varnish or its equivalent surface and fragmental or geometrical ornamentation, or both such ornamentation and a portion 55 of the base to which the veneer is applied, exposed to view.

In my pending application for a patent, filed October 5, 1882, the ornamentation of the varnish veneer therein described was produced by 60 either printing or painting or applying printed or painted ornaments upon the back of the varnish veneer or between layers of varnish, and by the transparency of the varnish having these ornaments visible to the sight. My present 65 invention is not intended to cover a veneer such as is claimed in such pending application.

In the accompanying drawings, Figure 1 is a front view of my improved veneer as applied 70 to a base or article, and with a portion of the foundation and protecting paper washed away to expose the surface of varnish or equivalent material and the fragmental ornamentation. In this illustration the fragmental ornamentation is shown as spread over the entire base or 75 article, save so far as the fragments are separated by the varnish, which embeds and holds them in position. Fig. 2 is a similar view to Fig. 1, excepting that the fragmental ornaments are arranged in parallel vertical panels, separated by intervening plain panels of varnish or equivalent material. Fig. 3 is a horizontal section of the veneer shown in Fig. 2 80 before being applied to a base or article. Fig. 85 4 is a similar view to Fig. 3, showing the veneer applied to a base. Fig. 5 is a horizontal section of the veneer as provided with both a paper foundation and paper or cloth backing. Fig. 6 is a horizontal section of Fig. 5 applied 90 to a base or article. Fig. 7 is a view illustrating one of many mosaic borders which may be adopted with my invention. This one is shown as formed of oblong rectangular pieces of wood or other material placed zigzag 95 upon a paper foundation and embedded in varnish or equivalent material; and Fig. 8 is a transverse section of a column with my veneer applied to it, ready to have the foundation paper removed.

In the views of the drawings, A is the protecting and supporting foundation paper or

cloth of the veneer. This foundation, when of paper, may be specially manufactured from pulp with reference to the use intended, so that the removal of it after the completion of 5 the veneer, and its application to a base or article, D, may be effected in a ready manner by disintegration of its fibers by saturating the paper foundation with water and rubbing off the paper with a sponge, or otherwise. 10 Neither the manner of making the paper nor kind used is important, so long as it can be removed without injury to the veneer or varnish or equivalent material. This foundation A is coated on one side with varnish or equivalent material at *a*, and upon this coat of varnish or equivalent I place either particles of pearl-shell, or fragments or pieces of any other suitable material—such as metal, stone, glass, 15 wood, bone, or a combination of any number 20 of the materials mentioned, or of other analogous fragmental materials—for the purpose of producing the ornamentation *b* of the veneer. This done, and the first coat, *a*, of varnish or equivalent material upon which the ornaments 25 were placed, having been allowed to dry or become perfectly set, I next completely cover the ornaments and the first coat of varnish or its equivalent with one, two, or more coats of varnish, *c*, and when these coats of varnish are 30 set, the veneer will have been completed, and can be cemented to a base or article, D. After the veneer has been applied to a base or article D, the foundation-paper can be removed by saturating it with water and rubbing off with 35 a sponge, or in any manner desired.

After applying the veneer, it may be rendered smooth or of uniform thickness by pressure applied against its foundation-paper, and this pressure may be produced upon a moderately-heated board or plate resting on the veneer, or by a moderately-heated iron. This done, and should slight imperfections be found to exist, the veneer may be rubbed down with pumice-stone to remove the imperfections, and 45 a thin coat of varnish to increase the brilliancy of the veneer may be applied to the surface after being rubbed down, as stated.

The veneer, if made of varnish, as herein described, may be applied to a base or article 50 D at any subsequent time after the last coat of varnish is applied and has become real “tacky,” and in such case this last coat of varnish will answer as the cementing material by which the veneer is cemented or fastened 55 upon said base or article D.

It will be understood that artificial heats may be adopted when baking-varnishes are used and a very hard surface is desired, while ordinary modes of drying will answer for veneers not required to be baked; also, that, either before or after the rubbing down of the veneer with pumice-stone, the veneer, if flat or level on its surface, may be pressed.

In very large surfaces I find it desirable in 60 some instances, when serious defects are found to exist after the veneer has been applied and

the foundation-paper A removed, to reapply foundation-paper and again subject the veneer to hot pressure applied through a heated board, plate, or iron, for the purpose of removing the imperfections. A veneer thus re-treated may be coated with varnish to heighten its brilliancy.

A veneer made in accordance with my invention as thus far described may present 75 either a continuous ornamentation, as in Fig. 1, or divided portions of ornamentation, as in Fig. 2. Of course, any design, configuration, or arrangement may be adopted, accordingly as fancy may suggest.

Another useful form of my veneer having fragmental ornamentations—such as pearl-shell or other fragments, or geometrical pieces of either circular, square, oblong, prismatic, octagonal, or other known forms of other suitable materials—such as metal, stone, glass, wood, bone, or a combination of any of the same within its body, as described, and supported by a paper foundation, A—would be to cement a backing, E, of either paper, cloth, or canvas, 85 to the rear surface of the veneer, and to apply cement or glue to the back surface of this backing, for the purpose of gluing or cementing the veneer to a base or article D. This form may be preferable to the other shown and described, as the paper or cloth E adheres very firmly to varnish, while the paper or cloth can be very firmly glued or cemented to the base or foundation D.

I propose in some cases to place the ornamental fragments directly upon the foundation-paper A, fasten them by other gummy substance than varnish, and then to embed them by one, two, or more coats of varnish. I propose, further, to have the ornamentation 100 consist of fragments of materials lying between layers of opaque varnish, so that the particles of material will fully show when the surface of the veneer is rubbed down sufficiently to expose them to view. I further propose to 105 substitute cloth for the paper foundation A, and I regard the same as an equivalent protecting and supporting device; but I prefer the paper material, as it can be readily removed by saturation with water and rubbing with a 110 sponge, and cloth is used as a backing in preference to paper whenever the veneer is dried by baking, inasmuch as it is less liable to warp and is much stronger, especially for large surfaces.

My improved veneer will be found very useful in connection with other materials to form mosaic borders, inlaid and other ornamental work, as illustrated in Fig. 7, in which figure A represents the foundation-paper; *b*, the ornamental or geometrical pieces, and *c* the varnish or equivalent material of which the veneer is made.

In manufacturing the veneer either transparent varnish or shellac may be employed; or 125 the transparent varnish may be rendered opaque by mixing with pigments of any color.

My veneering may in some cases be decorated on its finished surface by painting, if desired, and the veneering may be placed upon either cylindrical, elliptical, angular, lens-ticular, or flat surfaces; and the base upon which it is placed may be either convex, concave, or straight, and continuous on one plane or undulating or serpentine.

In the foregoing specification I have referred 10 to re-treating the veneer by pressure when it is found by the removal of the foundation material that imperfections in the surface exist; but I do not claim under this patent the process of either treating or re-treating veneer by 15 pressure, as I contemplate applying for a patent for a process or processes embracing the treating and re-treating of veneers by pressure.

I am aware of Letters Patent Nos. 97,607, 225,802, and 226,497, and make no claim for 20 anything shown therein; but

What I claim as my invention, and desire to secure by Letters Patent, is—

1. In a veneer, as herein described, the combination, with a paper or textile foundation, as A, of ornaments, as b, and a uniting and holding body, as c, whereby ornamenting-

veneering is provided, which can be applied to objects after their construction, and which is in a form not liable to injury or destruction from handling or during application to objects, 30 substantially as and for the purpose described.

2. In a veneer, the combination, with a textile backing, E, of embedded ornaments, as b, a uniting and holding body, as c, and a paper or textile foundation, as A, whereby ornamenting-veneering is provided, which can be applied to objects after their construction, and which is in a form not liable to injury or destruction from handling or during application to objects, and can have its surface smoothed 35 40 by pressure, substantially as described.

3. The new manufacture consisting of a pressed veneer having a uniting and holding body, c, embedded ornaments, as b, a paper or textile foundation, as A, and a paper or textile backing, E, substantially as and for the 45 purpose described.

FREDERICK KOSKUL.
